United States Patent Office

Des. 232,480
Patented Aug. 20, 1974

232,480

COMPUTER OUTPUT MICROFILMER OR THE LIKE

Thomas Cecil Laughon, Rochester, N.Y., assignor to
Eastman Kodak Company, Rochester, N.Y.

Filed Oct. 5, 1972, Ser. No. 295,409

Term of patent 14 years

Int. Cl. D16—03

U.S. Cl. D61—1 Q

FIG. 2

FIG. 1 is a top, left, and front perspective view of a computer output microfilmer or the like showing my new design;

FIG. 2 is a bottom, right, and rear perspective view thereof.

I claim:

The ornamental design for a computer output microfilmer or the like, as shown.
